[57] CLAIM

The ornamental design for a combined picture frame
and shelf unit, as shown and described.

DESCRIPTION

FIG. 1 is a front elevational view of the combined picture
frame and shelf unit showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front and upper right perspective view
thereof; and,

FIG. 8 is a cross-sectional view thereof taken along line
8—8 of FIG. 1.

FIG. 1

FIG. 2

FIG. 3

FIG. 4

FIG. 5
